BASEBALL GAME

Julius Caesar, Humboldt, Tenn.

Application April 17, 1944, Serial No. 531,424

8 Claims. (Cl. 273—90)

1

This invention relates to games, and more particularly to a gameboard for playing a game of baseball type.

The objects of the invention are:

To provide a game device including a playing board which may be manipulated by one of two contestants and which is provided with additional apparatus which may be manipulated by the other of the two contestants in a manner to accomplish a game simulating baseball; and more specifically

To provide a board so mounted or supported that it may be manipulated by one of the two contestants to propel a ball toward a batter, as in playing baseball, and if the ball be hit by the batter, may be caught by a fielder, or if not caught fielded by further manipulation of the board to put out the batter advancing to first base, or a runner, or runners, on base advancing to other bases, and in which board provision is made for manipulation by the second contestant of a batter in an endeavor to strike the ball and for further manipulation of a runner, or runners, and their advancement around the bases.

The means by which the foregoing and other objects are accomplished, and the manner of their accomplishment, will readily be understood from the following specification upon reference to the accompanying drawings, in which:

Fig. 1 is a plan view of a game board having a baseball field in miniature outlined thereon, with a batter, runner and fielding devices shown.

Fig. 2 is a sectional elevation taken on the line II—II of Fig. 1.

Figs. 3, 4, 5 and 6 are enlarged fragmentary views showing various details of construction;

Fig. 3 being a sectional elevation taken as on the line III—III of Fig. 6, showing one of several brackets supporting the infield or diamond relatively to the surrounding portion of the board;

Fig. 4 a sectional plan taken on the line IV—IV of Figs. 2 and 5, showing batter mechanism and runner advancing mechanism and the manipulating means therefor;

Fig. 5 a corresponding sectional elevation on the line V—V of Fig. 4; and

Fig. 6 a sectional plan on the line VI—VI of Fig. 2, immediately above the surface of the playing board, showing runners approaching first and second base and the ball having been manipulated to cut off the runner at first base.

Referring now to the drawings in which the various parts are indicated by numerals:

11 is a board which has a flat surface periph-

erally surrounded by a wall 13, and therewithin an additional or outfield wall 15, and walls 17. 19 is the infield which is separated from the surrounding field by a continuous slot 21 along which the runners are advanced from home plate 23 to the other bases, in manner simulating the way in which the players on a baseball field advance. Along this slot and extended therebeyond, the usual foul lines 24 are indicated.

20 Positioned at the bases are chair-shaped pockets 25, 27 and 29, representing first, second and third basemen, and outward therefrom are positioned two chairs 31 representing short stops, after the manner of soft ball, and three chairs 33 representing outfielders, these chairs hereinafter sometimes being referred to as basemen, and fielders. The chairs which represent the three basemen are preferably smaller than those representing the outfielders. These chairs may 25 otherwise be of the same type and are preferably each provided with loose mesh back portions against which the ball if propelled through the air on the fly, may strike substantially without bouncing.

25 Each of the chairs is provided with a rim 35 which assists in trapping the ball, particularly along the side, facing the batter, and with a seat portion having an opening 37 through which the ball 39, if trapped by the chair, drops 30 on the board for easier recapture and return to the fielder contestant for the next play. The chairs are each supported by two legs 41 which are spaced well apart to minimize interference with the ball when it is rolling on the board.

35 The first, second and third basemen are positioned over their respective bases, the legs 41A of the first baseman being on opposite sides of and at equal distances from the base and so spaced apart that with a runner 43 in the dotted 40 position 43A, of Fig. 6, that is, having reached the base, passage of the ball 39 is blocked whether it be to the one side or the other of the runner. The third baseman, not shown in Fig. 6, is similarly positioned with regard to that base and the legs 41B of the second baseman are positioned

45 as shown and accomplish similar blocking with a runner on second base, such blocking indicating that the runner is safe on the plays. The first and third base chairs are preferably additionally provided on their outer sides with wings 50 25W, 29W respectively, which divert inward the ball being fielded toward first or third base, as the case may be, and make fielding of the ball somewhat easier.

55 Beneath the board is a channelway 45 which

extends from an opening 45A in the outfield end of the board to a second opening 45B in the infield, which may be designated as the pitcher's box, the channel being preferably deepened intermediate its length to clear other apparatus below the board, and preferably having its sides 44 continued to the batter end of the board. The ball 39 is dropped into the channelway 45 through the opening 45A and after traversing the channelway is projected from the pitcher's box 45B upwardly and rearwardly across home plate 23 in a trajectory or path P, somewhat as shown in Fig. 2.

The inner or batter's end of the board has a centrally disposed supporting post 47, which projects downwardly from the board and is preferably provided at its lower end with a suction cup 47A adapted to rest on and adhere as to the top of a table 49. When not in play the outer part of the board may be lowered to rest on the table, but in play is supported by the hands, of the player representing the team in the field.

The infield 19 is separated from surrounding portions of the board 11 by the continuous slot 21 and is supported in such position by brackets or cleats 51, which are cut away at 51A beneath the slot. Journalled below the four corners of the infield are sprockets 53, having vertical shafts, these sprockets carrying an endless chain 55. Disposed at equal distances along this chain are four open top vertically disposed sockets 57 adapted to receive the runners 43, which may be indiscriminately placed in or removed from such sockets as occasion may require.

The sprocket 53A at home plate is secured on a shaft 59, on which is also secured a bevel gear 61. Gear 61 meshes with a second horizontally disposed shaft 65 extending through and journalled in the post 47. Secured on the outer end of the shaft 65 is a hand wheel 67 which is adapted for manual manipulation by the contestants representing the team at bat.

69 is a batter who carries a bat 71. The batter is mounted on, and turns with, a vertically disposed post 73, suitably journalled. Also secured to this post is an arm 75 which is urged toward batting position by a tension spring 77, the arm being disposed through slots 79 in the sides 44 of the channelway. The arm 75 extends beyond these slots and is provided with a grip portion 75A which is engaged by the finger of the operator to retract the arm, turn the batter, and retract the bat which he carries, release of the finger grip allowing the spring to swing the bat toward the ball.

81 is a flexible bumper against which the arm is swung by the spring 77 on release of the grip 75A. Movement of the arm swings the bat in a horizontal arc, in a path intersecting the usual trajectory path of the ball 39 as it is delivered from the pitcher's box 45B.

In using the device the board is placed on a table, as the table 49, with the suction cup 47A engaging the table adjacent one edge thereof, and the outer end of the board rested on the opposite edge of the table. The contestants arrange themselves one as a fielding contestant, in adjacency to the outer end of the board, and the other as a batting contestant, in position to operate the hand wheel 67, and the grip end 75A of the arm 75. A runner 43 is placed in the chain socket 57 adjacent home plate, the other sockets being left empty, and the game begins. The ball 39 is dropped by the fielding contestant through the hole 45A into the channelway 45 and, by rea-

son of the slope of the channel toward the outfield, remains at the outer end of the channel. He then grasps the two sides of the outer end of the board in his hands and raises the board quickly to a position, such as is shown in Fig. 2, establishing a downward path for the ball 39 to the pitcher's box and endeavors to establish such slope of the channelway that the ball will be delivered over home plate in an arc or trajectory path similar to the path P, indicated in such Fig. 2.

The batting contestant retracts the arm 75 by pull on the grip 75A against action of the spring 77 and awaits the pitch and delivery of the ball. As the ball is delivered he endeavors to release the grip at proper time to swing the bat and hit the ball, as does the batter when he swings at a ball thrown in the game of baseball. If he is unsuccessful a strike is recorded, three strikes, as usual, constituting an out. If on the other hand the fielding contestant fails to deliver the ball in a proper trajectory over the plate, a ball is recorded, the usual four balls being allowed before the batter is given his base.

Should the bat strike the ball and project it forwardly of the plate and within the foul lines 24, it is, as in a baseball game, a fair ball. If batted on the fly, the ball strikes in one of the basemen's chairs or fielder's chairs and does not bounce out, it is an out, although obviously thereafter it drops down and rolls through the hole 37 in such chair for recapture for the next play. If the ball bounces out it is an error and the ball must be fielded to a base to get the batter out, or if the ball is hit into the playing field on the fly, or on the board, it must similarly be fielded toward a base. The batting contestant, having swung the bat and hit the ball, grasps the hand wheel 67 and turns it to actuate the chain 55 and advance the runner 43 positioned adjacent home base toward first base. The fielding contestant tilts the board laterally and longitudinally, as he may see fit, and endeavors to roll the ball along the surface of the board toward first base in an effort to roll the ball between the legs 41A of the first baseman before the runner, advanced by turn of the wheel 67, reaches that base.

In fielding this ball advantage may be taken of the side walls 13, or the wing 25, or even the wall 17 to assist in getting a ball to the base in time to head off the runner, it being immaterial whether the ball approaches the base from the outfield or from some other direction. If the ball passes between the legs of the first baseman before the runner reaches such base, the runner is out, and this out is recorded even though the ball hit the runner after it passes between the baseman's legs and is bounced back by the runner approaching the base. If, however, the runner reaches the base before the ball, and passage of the ball is blocked by the runner and the baseman's legs, the runner is safe. Should the fielder find that he is unable to make the play at first base and the batting contestant elects to advance the runner past such base toward second, the play may be continued in an endeavor to head the runner off at second, or at third, or at home plate. When a runner has reached first base an additional man is placed in the socket at home plate and on the next hit by the batsman play may be made at second base for a forced out and continued to first base for a double play. Runners being advanced may be returned toward bases they have

left, but if cut off in attempting such return are out, and may be doubled off base if they overrun when a fly is caught.

When three outs have been made the contestants shift position, the batting contestant changing to fielding contestant, and the fielding contestant coming to the plate and becoming the batting contestant, these positions being alternated for the usual nine innings.

Strikes, balls, outs, and hits may be recorded, and runs are scored in the usual manner of baseball scoring, though in usual practice only the runs will be scored, and as in a ball game, the side making the most runs is obviously the winner.

It will be understood that the post 47 might be moved away from the batter end toward the outfield end of the board, so long as the shift toward the outfield end be not sufficient to interfere with the sharp longitudinal tilting of the board which is necessary to deliver the ball in pitching. However, it is distinctly preferable that the post be adjacent the edge of the board at the batter end in order that movement of the control apparatus, operated by the batter contestant, be minimized and such contestant be not seriously interfered with in his operation of the batter and advancement of the runners.

The ball preferably is of soft rubber, but if not of rubber is of such resiliency that when struck by the bat it may be driven to the outfield and even occasionally over the wall 15 at the outfield end, in which latter case a home run is scored.

It will be noted that the legs of the chairs, as the leg 41B of the chair 27, in Fig. 2 shows, are inserted in holes in the board surface. Should it be desired, additional holes 83, Fig. 1, which laterally are spaced to conform to the leg spacing of the chairs, may be provided, into which the legs of the shortstop chairs 31 may be transferred to shift the positions of these chairs, laterally and/or forwardly, and similarly holes 85 for shift of the outfielder chairs 35, such shift being optional with the fielder contestant, as where a batting contestant consistently hits to the left or right, or short.

The pitcher's box 45B is preferably surrounded by a wall 87 which, as seen in Fig. 2, extends above the board surface, this wall preventing the ball, while being rolled along the board, from dropping through the board and also assisting in forming a pocket, in addition to the fielder chairs, into which, if the ball on the fly drops, the batter is out.

At home plate the corners 89 of the walls 17 co-operate with a runner crossing home plate, as do the legs of a baseman with the runner at the related base in blocking passage of the ball across the base and indicating that the runner is safe.

The sockets 57, Fig. 3, which carry the runners 48, do not project above the board surface so that when not carrying a runner they do not interfere with fielding the ball.

It will be understood also that the use of the tension spring 77 to effect the batter's swing is typical only of means for this purpose, and that except where set out in a claim, it is not my intent to limit myself to the specific detail set out.

I claim:

1. In a game apparatus, a manually manipulable board, a ball, a batter, batting means, and runners, carried by said board, said board being marked to simulate a baseball diamond, and field, means adjacent the batter end of said board sup-

porting said board for universal tilting movement, means forming a pathway for advancement of said runners from base to base, means for advancing runners along said pathway, means at the batter's end of said board for actuating said batter and adjacent means for actuating said advancing means, a channelway for said ball underlying, and extending from the outfield and toward the batter's end of, said board, the outfield end of said channelway being open to receive said ball, and its opposite end curving upwardly through said board forwardly of said batter for delivery of said ball to said batter, means at the bases and additional means in the field for trapping balls batted on the fly, said trapping means at the bases, respectively having support members positioned on opposite sides of their related said bases, spaced to allow free passage of said ball over the base when unoccupied, but restricted to cooperate with a said runner advanced to the base to block passage of the ball.

2. In a game apparatus, a board, a batter and runners, carried by said board, and a ball, said board being marked to simulate a baseball diamond and surrounding playing field, means supporting said board for universal tilting movement, means forming a pathway for advancement of runners from base to base, means for advancing runners along said pathway, means for actuating said batter, and means for operating said advancing means; a channelway for said ball underlying, and extending from the outfield and toward the batter's end of, said board, the outfield end of said channelway being open to receive said ball, and its opposite end curving upwardly through said board forwardly of said batter, for delivery of said ball, means at the bases and additional means in the field for trapping balls batted on the fly, said trapping means at the bases, respectively having support members positioned to cooperate with a runner occupying a base, to block passage of the ball, but allowing free passage when said base is unoccupied.

3. In a game apparatus, a manually manipulatable board carrying a batter, a runner, and a ball, said board being marked to simulate a baseball field, means supporting said board for universal tilting movement, means forming a pathway for advancement of runners from base to base, means for advancing runners along said pathway, manual means for actuating said batter and means for operating said advancing means, and means forming part of said board operable by longitudinal tilt of said board for delivery of said ball to said batter, means at the bases and additional means in the field for trapping balls batted on the fly, said trapping means at said bases respectively having support members positioned to cooperate with a runner on base to block passage of the ball, but permitting free passage of said ball when said base is unoccupied.

4. In a game device, a ball, and a playing board marked to simulate a baseball diamond and field, said board carrying means for trapping fly balls, a batter, and removable runners on the base lines; means, at the batter end of said board respectively for actuating said batter and means for advancing said runners from base to base, means adjacent the batter end of said board effecting universally tiltable support thereof, said board being adapted for manual support at its outfield end to effect pitching delivery and subsequent fielding of said ball, certain of said trapping means being respectively placed at the bases and each including supports spaced apart

to allow free passage of the ball across the related base when unoccupied, but to block passage of the ball when a runner occupies the related said base.

5. In a game apparatus, a manually manipulable board, a ball, batting means, and means adjacent the batting end of said board supporting said board for universal tilting movement, means at the batter's end of said board for actuating said batting means, a channelway for said ball underlying, and extending from the outfield and toward the batter's end of, said board, the outfield end of said channelway being open to receive said ball, and its opposite end curving upwardly and opening through said board forwardly of said batting means for delivery of said ball upwardly and rearwardly past said batting means, under manual raising movement of the end of said board opposite said batting means to propel said ball.

6. A game device including a ball, runners and a board mounted for manual tilting to field said ball along its surface, said board having outlined thereon a baseball diamond, including bases; means for advancing runners from base to base, and means, respectively each at a said base, spaced to permit free passage of said ball across an unoccupied said base, but adapted to block passage when said base is occupied by a runner.

7. A baseball game device for operation by two contestants, said device including a board marked to simulate a baseball field, and a ball, said board

having mounted on one end thereof, means manually operable by one of said contestants, for batting said ball, and beneath said end a single downwardly extending post supporting said board end in raised position for universal tilting movement, said boards being manually tiltable by the other said contestant to deliver and field said ball, said post being immediately adjacent said batting means, whereby to minimize movement of said manually operable means with respect to the contestant operating said means, while said board is being tilted by the other said contestant to accomplish delivery of said ball.

8. A baseball game device for operation by two contestants, said device including a board marked to simulate a baseball field, a ball, and runners, said board having mounted on one end thereof means for batting said ball, and adjacent means for advancing said runners, both manually operable by one of said contestants, and beneath said end a single downwardly extending post supporting said board in raised position for universal tilting movement, said board being manually tiltable by the other said contestant to deliver and field said ball, said post being immediately adjacent said batting and advancing means, whereby to minimize movement of said manually operable means with respect to the contestant operating said means, while said board is being tilted by the other said contestant to accomplish delivery and fielding of said ball.

JULIUS CAESAR.
